STEAM GENERATION

After Douglas La Mont, Larchmont, N. Y., assignor to La Mont Corporation, New York, N. Y., a corporation of New York

Original application January 23, 1926, Serial No. 83,235. Divided and this application April 19, 1929, Serial No. 356,406. Renewed December 20, 1934

18 Claims. (CL 122—39)

This invention relates to a specific arrangement of steam generating elements and superheating elements and is a division of my application Serial No. 83,235, filed January 23, 1926, for 5 "Steam generation".

In said prior application I have shown and claimed an arrangement for controlling the superheat of steam wherein the flow of steam through the superheater elements is subjected to the same 10 progressive change of temperature corresponding to that to which the steam generating elements themselves are subjected. In said application there is also described and claimed the control of the temperature of the superheated steam by 15 varying the amount of steam passing through different elements of the superheater.

The present application relates to a specific arrangement of steam generating and superheater elements embodying the broad principles of the 20 parent case but directed more particularly to a construction whereby the velocity of the heating gases throughout its passage over the steam generating elements and superheater elements is maintained. The invention is illustrated in the 25 accompanying drawing in which

Figure 1 shows a section through the generator.

Figure 2 shows water restricting means at the inlet ends of the tubes.

The generator consists in an integral lower 30 header or pot 282 and three separate upper headers 283, 284 and 285 connected to the pot by the tubes 286, 287 and 288. The three sets of tubes are separated by the two baffles 289 and 290 and thus form three passes. The gas flow as shown 35 by the arrows is upward through the first pass, downward through the second and upward through the third. The baffles are so inclined and the spacing of the tube connections on the headers is so proportioned that the cross-section of 40 each pass decreases continuously in proportion to shrinkage in volume of the combustion gases as they are cooled in passing over the tubes. The first and third passes are provided with water injection into the headers 283 and 285 by means 45 of the pump 291, pipe 292 and branch pipes 293 and 294 provided with the valves 295 and 296. The feed water is added to the pump circulation 50 through the pipe 297 provided with the valve 298 which is actuated by the water level control 299. Superheated steam is taken off from the headers 284 through the pipe 300.

The operation of the generator is as follows: For normal low ratings the valves 295 and 296 55 are so adjusted that the amount of water introduced into the tubes 286 is greater than that which

can be evaporated by passing therethrough and accordingly saturated steam and water is discharged in the lower portion of the pot 282. The amount of water introduced into the header 285, however, is less than that which can be evaporated in the tubes 283 and accordingly superheated steam is discharged from these tubes into the upper portion of the pot. The saturated steam from the tubes 286 and moderately superheated steam from the tubes 288 then flows up 10 through the tubes 287 where it is further superheated. As the boiler rating increases, a larger and larger quantity of water is introduced into the header 285 so that the steam discharged from the tubes 288 is of a lower and lower superheat 15 temperature and finally is discharged in the form of saturated steam.

It will be seen that the hottest gases in the first pass come in contact with tubes which are supplied with an ample amount of water and are 20 not subject to danger from irregular running of the boiler or sudden increase in flame temperature. The superheater tubes 287 are in the zone of sufficiently low heat so that they are not in danger of burning out. The generating tubes 288 25 situated in the lowest heat zone, subsequently abstract from the cooled gases their last quota of heat so that the gases passing out to the stack may be in ordinary operation at or near the temperature of the water introduced into the header 30 285.

Where the flame is not extreme in temperature or where the pot and generating tubes 286 are made of particularly resistant metals, it is 35 possible to generate superheated steam in the tubes 286 as well as in the tubes 288 by restricting the water flow through the valve 295. This makes possible a very high superheat since the superheater tubes 287 are not fed with saturated steam but are fed with steam which is already 40 superheated.

Manually operated valves 295 and 296 have been shown, but it is of course obvious that a thermostat can be placed in the superheated steam pipe 300 and used to automatically operate the valve 296 in order to control the superheat by control of the temperature of the steam generated in the tubes 288. For most purposes it is desirable to use manual control on the valve 295 or if an automatic control is desired 50 this is preferably actuated by the water level 299 as it is important in most installations to assure a continuous and plentiful supply of water to the tubes in the first pass to prevent their burning out. Where, however, in unusual in- 55

stallations it is desired to generate superheated steam in the tubes 286, the valve 295 can, of course, also be controlled thermostatically in accordance with the temperature of the superheated steam in the pipe 300. Other methods of control may also be used and are included in the invention.

Also, as described in my application Serial No. 83,235 above referred to, the steam generating tubes may be provided with means at their water inlet ends for restricting the flow of water delivered to the tubes. As described in my Patent No. 1,545,668 dated July 14, 1925, this flow may be in amount less than sufficient to fill the tube while providing an amount greater than the evaporation within the tube.

In Figure 2 of the drawing is shown a section of a header 305 which may be, for example, one of the transverse headers to which tubes 286 are connected at their upper ends and which is connected to the header 283. Within the header 305 may be fitted an orifice tube 306 having openings or orifices 307 therein registering with the upper ends of the tubes 286. The water entering the orifice may thus be distributed to and injected into each of the tubes 286 through the orifices 307, said orifices providing means for restricting the flow in the manner referred to above and as disclosed in said application and patent.

The design and shape and the number of passes may be varied greatly depending on operating conditions and on the space available. It is thus perfectly practicable to use a double pass omitting the tubes 288. A saving in space is effected at the expense of reliability of superheat control and also at the expense of efficiency as it is relatively difficult with a practical number of tubes to reduce the gas temperature in the superheater pass to the temperature of the saturated steam entering it, whereas it is a very simple matter to reduce the gas temperature to or near that of the intake water when the last pass contains generating tubes owing to the very high heat absorption of the water film in the tubes. It should be understood, however, that the principles of the invention are in no sense limited to the three-pass generator shown, which, however, constitutes the preferred embodiment of my invention and, as pointed out above, combines a maximum of efficiency and reliability of temperature control with compact arrangement and reasonable draft pressure.

The header, tube and pot construction of the three-pass generator and superheater described above may, of course, be greatly varied within the scope of the present invention. The drawing is purely diagrammatic and is not intended to show structural details with which, in its broader aspects, the present invention is not concerned. The separate top header construction, shown for the sake of simplicity, is efficient and practicable, but many other modifications may be utilized.

What is claimed as new is:

1. An apparatus for generating superheated steam comprising a plurality of tubes, a common header to which one end of each of the tubes is connected, means for so positively delivering water to the tubes to be used for steam generation at the ends thereof remote from the header and causing the same to flow unidirectionally therethrough that the steam generated therein is discharged into the header, and means for withdrawing from the other tubes connected to the header at the ends thereof remote from the head-

er the steam received from the header whereby the steam is caused to flow through these tubes and become superheated.

2. An apparatus for generating superheated steam comprising steam generating tubes all extending in the same general direction, superheating tubes extending in the same general direction, a common header to which one end of each of the tubes is connected, means for so positively delivering water to the ends of the steam generating tubes remote from the header, as to cause the water to flow unidirectionally through said tubes and to discharge the generated steam into the header, and means for discharging from the ends of the superheating tubes remote from the header the steam received therefrom by these tubes.

3. An apparatus for generating superheated steam comprising steam generating tubes all extending in the same general direction, superheating tubes extending in the same general direction as the steam generating tubes, a common header to which one end of each of the tubes is connected, means for delivering water to the ends of the steam generating tubes remote from the header, so as to cause the steam generated to discharge into the header, means for discharging from the ends of the superheating tubes remote from the header the steam received therefrom by these tubes, and means for causing heating gases to pass in counterflow relation to the flow of steam through the tubes.

4. An apparatus for generating superheated steam comprising tubes to one end of which the water for steam generation is delivered, other tubes from one end of which the steam after being superheated therein is discharged, a chamber connected to the remaining ends of all the tubes for separating from the steam any water contained therein before it becomes superheated, and means for returning the water to the input ends of the tubes for steam generation and for positively causing flow of the water through said tubes toward said chamber.

5. An apparatus for generating superheated steam comprising two spaced sets of steam generating tubes all extending in the same general direction, a set of superheating tubes located therebetween and extending in the same general direction as the steam generating tubes, a common header to which one end of each of the tubes of all the sets is connected, means for positively delivering water to that end of each of the steam generating tubes remote from the header and discharging the steam generated into the header, and means for withdrawing from the ends of the superheating tubes remote from the header the steam flowing through these tubes from the header.

6. An apparatus for generating superheated steam comprising a plurality of sets of tubes arranged adjacent to each other and all extending in the same general direction, walls enveloping said tubes to form a chamber for confining heating gases, a partition wall between adjacent sets of the tubes and extending in the same general direction as the tubes to form adjacent passages through which the heating gases flow successively in intimate contact with the sets, a single header connected to all the tubes at one end of each set, means for so positively delivering water to some of the sets of tubes at the ends thereof remote from the header that the steam generated therein is discharged into the header, and means for withdrawing from the

other sets of tubes connected to the header at the ends thereof remote from the header the steam received by said tubes from the header.

7. An apparatus for generating superheated steam comprising walls forming a chamber for confining heating gases, partitions mounted within said chamber in such relation to each other and to the walls as to form a continuous sinuous passage, steam generating and superheating tubes extending in said passage lengthwise thereof, means for positively delivering the water for steam generation to each of the steam generating tubes adjacent one end of a portion of the passage so as to cause the generated steam to be discharged adjacent the other end of a portion of the passage, means for delivering the steam to be superheated to the superheater tubes adjacent one end of a portion of the passage, means for discharging steam from the opposite ends of the superheater tubes, and means for causing the gases to flow through the passage from one end thereof to the other.

8. An apparatus for generating superheated steam comprising walls forming a chamber for confining heating gases, partitions mounted within said chamber and converging in relation to each other and the walls so as to form a continuous sinuous passage of progressively reducing cross sectional area in one direction of its length, tubes extending in said passage lengthwise thereof and more closely spaced adjacent their ends which lie in the portion of the passage having less cross sectional area relative to the portion adjacent their other ends, means for delivering water to some of the tubes and the steam to be superheated to other tubes at the ends thereof which respectively lie adjacent the portions of the passage of less cross sectional area, and means for causing the gases to flow through the passage toward the end thereof having smaller cross sectional area.

9. An apparatus for the generation of superheated steam comprising steam generating tubes and adjacently arranged superheating tubes extending in the same general direction as the steam generating tubes, walls enclosing the tubes and forming a chamber for confining the hot gases introduced therein, partition walls in said chamber placed between certain of the tubes and converging in such relation to each other and to the walls of the chamber as to form passages adjacent to each other through which the gases flow successively and in intimate contact with the tubes, said passages having a cross sectional area which reduces in the direction of the gas flow, a common header located adjacent one end of both steam generating and superheating tubes into which header the steam generating tubes discharge the steam generated therein and from which at the same end the superheating elements receive the steam to be superheated, and means for positively delivering water to that end of all the steam generating tubes which is remote from the header.

10. An apparatus for the generation of superheated steam comprising steam generating tubes and adjacently arranged superheating tubes extending in the same general direction as the steam generating tubes, walls enclosing the tubes and forming a chamber for confining the hot gases introduced therein, partition walls in said chamber placed between certain of the tubes and converging in such relation to each other and to the walls of the chamber as to form passages adjacent to each other through which the gases

flow successively and in intimate contact with the tubes, said passages having a cross sectional area which reduces in the direction of the gas flow, a common header located adjacent one end of both steam generating and superheating tubes into which header the steam generating tubes discharge the steam generated therein and from which at the same end the superheating elements receive the steam to be superheated, and means for positively delivering water to that end of all the steam generating tubes which is remote from the header, said header being so located in relation to the flow of gas over the superheater tubes that the flow of steam in the superheater tubes is in counter direction to the gas flow.

11. An apparatus for generating steam, comprising a plurality of tubes arranged adjacent to each other and extending in the same general direction, walls enveloping said tubes to form passages for confining heating gases in intimate heat exchanging contact with the tubes, a header at one end of the tubes to which all the tubes are connected in common, a plurality of manifolds at the other end of the tubes to which the tubes are connected in sets, means for delivering the water for steam generation to some of the manifolds and causing it to flow positively through the tubes of their sets toward the header, and means for discharging the steam received by the manifolds of other sets of tubes, whereby these tubes are used as superheater tubes, the passages being so connected that the flow of gases is counter to the flow of steam in the superheater tubes.

12. An apparatus for generating superheated steam comprising a plurality of closely spaced tubes of small diameter and all of the same length and all extending in the same general direction, walls closely enveloping said tubes to form a chamber for confining heating gases in intimate heat exchanging contact with the tubes, partition walls placed between certain of the tubes and extending in the same general direction therewith and converging to form with the walls of the chamber adjacent portions of a continuously tapering sinuous passage, water manifolds connecting the ends of the steam generating tubes which are adjacent the smaller extremities of the portions of the passage in which these tubes lie, a pump for delivering water to said manifolds in excess of the steam generating capacity of the tubes, a header to which the other ends of the steam generating tubes and the adjacent ends of the superheating tubes are connected in which the steam and water discharged from the steam generating tubes are separated, a connection from said header to said pump whereby the excess water is returned to said water manifolds, a steam manifold adjacent the larger end of the portion of the passage in which the superheating tubes lie to which are connected the ends of these tubes remote from the header so as to collect and discharge the steam flowing from said header through said tubes, and means for causing the heating gases to flow through the passages in counterflow relation to the flow of water and steam in the tubes.

13. Apparatus for generating superheated steam comprising steam generating tubes, means for so positively delivering water to one end of each of said tubes as to cause it, together with the generated steam, to flow through the tubes toward the other end thereof while preventing return flow of the water through said tubes, a chamber connected to said other ends of the tubes

for collecting the steam and for separating therefrom any water discharged therewith from the tubes, superheater tubes connected at one end thereof to said chamber, and means for withdrawing from the other ends of said superheater tubes the steam received from said chamber.

14. Apparatus for generating superheated steam comprising a plurality of tubes, a header to which all the tubes at one end thereof are connected, means for causing water positively to flow through certain of the tubes used as steam generating tubes toward the header while preventing return flow of the water through said tubes, and means for withdrawing superheated steam from the ends of other tubes remote from the header.

15. Apparatus for generating superheated steam comprising a plurality of tubes, a header to which the tubes at one end thereof are connected, means for positively delivering to certain of the tubes at the ends thereof remote from the header water in quantity in excess of the steam generated in said tubes but in quantity less than sufficient to fill the cross sectional area thereof, said header serving to separate the excess water from the steam discharged thereinto, and means for withdrawing from others of the tubes connected to the header at the ends thereof remote from the header the separated steam received from the header by said tubes and superheated therein.

16. Apparatus for generating superheated steam comprising walls forming a chamber for confining heating gases, partitions mounted within said chamber so as to form with said walls a continuous sinuous passage, steam generating and superheating tubes each having its inlet end at

a point in the passage at a distance from its respective outlet end, means for positively delivering water to the steam generating tubes at the inlet ends thereof and discharging steam at the outlet ends thereof, means for delivering steam to the inlet ends of the superheated tubes and discharging the superheated steam from the outlet ends of said superheater tubes, and means for causing the gases to flow through the passage in counter flow relation to the flow of steam in the superheater tubes.

17. An apparatus for generating superheated steam, comprising at least two tubes, a common header to which one end of each of the tubes is connected, means for delivering water to one of the tubes to be used for steam generation at the end thereof remote from the header, means associated with said tube for insuring unidirectional flow of the water through said tube toward the header together with the steam generated therein, and means for withdrawing from the other tube at the end thereof remote from the header the steam received from the header and superheated in said other tube.

18. An apparatus for generating superheated steam, comprising a plurality of tubes, a common header to which one end of each of the tubes is connected, means for withdrawing from some of the tubes at the ends thereof remote from the header steam received from said header by said tubes and superheated therein, means for delivering water to the remaining tubes at the ends thereof remote from the header, and means at said ends of said remaining tubes for insuring the distribution of the water to each tube and its flow therethrough toward the header.

WALTER DOUGLAS LA MONT.
